UNITED STATES PATENT OFFICE.

LOUIS N. SINGIN, OF WALLS, PENNSYLVANIA.

CAR-COUPPLING.

1,045,334.

Specification of Letters Patent. Patented Nov. 26, 1912.

Application filed May 23, 1910. Serial No. 562,960.

To all whom it may concern:

Be it known that I, LOUIS N. SINGIN, a citizen of the United States, and resident of Walls, county of Allegheny, State of Pennsylvania, have invented certain new and useful Improvements in Car-Couplers, of which the following is a specification.

This invention relates to car couplers, and particularly to automatic couplers of what 10 is known as the vertical plane type, and this invention is an improvement of the device shown in my prior Patent No. 497,930, granted May 23, 1893.

In the class of couplers described in the 15 patent referred to, the locking means will by creeping action tend to move to unlock- ing position.

One of the objects of this invention therefore is to provide an anti-creeping device 20 which will prevent the creeping of the lock- ing member.

The knuckle is generally pivoted to the draw head by means of a pivot pin. Now it often happens that this pivot pin will 25 be broken due to the enormous strain on it, and another object of this invention therefore is to provide a supplemental means which will hold the parts in position if such breakage occurs.

30 Another object is to place the material of the knuckle members where the strain will be the greatest so as to utilize the ma- terial with the greatest efficiency.

Another object is to combine with the 35 draw head a valve casing for the air and steam connections, and interconnect a valve for this casing with the knuckle in such a manner that they may be operated simultaneously when the cars are coupled.

40 Further objects will appear from the de- tail description.

The invention will be described in con- nection with the accompanying drawings, in which—

45 Figure 1 is a view showing the abutting ends of two cars with the invention applied thereto, one of the couplers being shown in section; Fig. 2 is an end view of a car showing the invention applied thereto; Fig. 3 50 is a section showing the locking and anti-creeping device; Fig. 4 is a similar section showing the parts in another position; Fig. 5 is a similar section showing the parts in a third position; Fig. 6 is a section on the 55 line 6—6, Fig. 4; and Fig. 7 is a section on the line 7—7, Fig. 6.

The couplers on the cars are of similar but complementary construction, and therefore the description of one will be sufficient.

Referring to the drawings, 10 designates 60 the draw head in which is pivoted a knuckle 11 by a pin 12 passing through the knuckle and the draw head. The knuckle is pro- vided with a segment provided with teeth intermeshing with a locking segment 13, 65 which is secured to an angular portion 14 of the shaft or stem of a valve hereinafter more particularly referred to. The inter- meshing teeth of the movable jaw or knuckle and the locking segment are indicated by the reference character 15. The segment 13 has a locking tooth provided with a locking shoulder 16 which coöperates with a lock- 70 ing pin 17 which is L-shaped or angular in section and provided with a portion 18 which 75 engages the shoulder 16 as shown in the drawings. The locking pin is provided with a guide portion 19 which extends through the draw head in a similar manner as shown in my prior patent referred to. The lock- 80 ing pin has formed thereon, an ear 21, and a pivotal member 22 is pivoted on the lock- 85 ing pin by a pivot pin passing through this ear and the locking pin body. This pivotal member is provided with a head 23 which is adapted to coöperate with a cam shaped portion 24 on the segment 13. The pivotal member is further provided with a toe 25 for a purpose hereinafter to be described. A 90 sliding member 26 angular in section ex- tends through the cap 20 of the locking pin, and is connected to the pivotal member by means of a loop or bail 27 which passes through an elongated slot 28 in the sliding member. The loop or bail is provided with 95 an enlarged end 29 through which passes a pivot pin to pivotally connect this loop with the pivotal member. The slot 28 is elongated so that the enlarged ends may pass therethrough, when the loop is placed in 100 position. The sliding member 26 is cut away as shown at 30 an amount equal to the thickness of the loop. The sliding mem- 105 ber 26 is preferably square in section and arranged to form with the pin 17 a square member which is arranged to slide in a square hole in the draw head. This mem- 110 ber is provided with a cap 32 and an ear 31 which is arranged to be connected by means of a chain 33 to an arm 34 on a mov- able shaft 35, mounted in bearings 36 on the car body, and the shaft 35 is provided

with an operating handle 37 so that the shaft may be oscillated to raise and lower the locking pin.

The teeth 15 are of ordinary construction but the tooth 38 on the knuckle segment and the tooth 39 on the operating segment are enlarged as shown for the purpose hereinafter to be described. The draw head is provided with inwardly extending bearing lugs 40 which coöperate with similarly shaped recesses 41 in the knuckle. These bearing lugs and recesses form a supplemental pivotal bearing as will appear later. The draw head is formed so as to provide shoulders 43 and 44 against which the segments abut when the knuckle is in closed and locked position.

The draw head has formed thereon or cast integral therewith a valve casing 45 provided with flanged extensions 46, which are arranged to receive rubber nipples 47 provided with flanges 48, whereby these nipples may be secured to the valve casing by means of rings 49 and fastenings, extending through the rings and flanges on the nipples and extensions respectively. Springs 50 are further interposed between the nipples and the casing body so as to press these nipples outwardly. As shown there is a rotatable valve 51 within the casing 45, which valve is provided with ports 52, 53, whereby it is adapted to control the passage of fluid through both the air and steam pipes. The stem or shaft of said valve extends upwardly through the casing of the draw head and is provided therein with the angular portion 14 to which the segment 13 of the coupler is secured as before described. The air pipe 54 has an extension 56 which is connected to the whistle. Suitable valves 57 and 58 are provided to close connections. The valve stem has connected to its lower end an arm 59 which is pivotally connected to a bar 60, provided with a boss 61 which slides on the shaft 35. This bar 60 is further provided with a suitable handle 62 so that the device may be manually operated. The valve stem or shaft 51 is maintained in position by means of a nut 63 and a cotter pin 64, and terminates above the casing 10 in a portion 65 angular in cross section on which may be fitted any suitable handle or turning means.

In Figs. 2 and 3, the knuckle is shown in open position. In this position, the lower edge *a* of the locking pin and the edge *b* of the pivotal member 22 will rest on top of the segment 13. It will be understood that the weight to the left of the member 22 due to the member 26 is greater than the weight on the right, so that this member will be maintained in position shown in Fig. 3. If now, the knuckles are interlocked and closed, the knuckle and segment 13 will be rotated to the position shown in Figs. 4 and 6, the

shoulder 16 will pass from underneath the lower edge *a* of the locking pin and this locking pin can now be dropped and ordinarily will be dropped by gravity to the position shown in Figs. 4 and 6. In this position the edge 18 will engage the shoulder 16, and the end 23 of the pivotal member will engage the edge 24 of the segment. In this position, the knuckle will be firmly and securely locked in closed position. The segment 13 is undercut at 24 so as to form a cam or wedging surface which coöperates with the similarly shaped surface 23. If now, there is any tendency for the locking pin to be raised as by creeping action, or, in other words, if a force be applied to the bottom of the guide 19, the pivotal member 22 will wedge against the segment 13 so that all upward movement of the locking pin due to creeping action is prevented. When however, the pin is raised by operating the handle 37, then the pivotal member 22 which forms an anti-creeping device is swung on its pivot so as to free the end 23 from the surface 24, permitting the entire pin to be raised to unlocking position shown in Fig. 5. As this pin is moved to unlocking position, the end of the toe 25 will engage the draw head as shown in Fig. 5, and will maintain the pin in unlocking position. The pivotal member 22 therefore forms not only an anti-creeping device but also a lock for holding the pin in unlocked position. In Fig. 5 the segment 13 is unlocked but the knuckle is still in closed position. If now the knuckle be moved to open position shown in Fig. 3 as by the cars moving away from each other, or by operating the handle 62, the segment 13 will move underneath the shoulder *a* and will contact with the edge *b* to move the pivotal member 22 to the position shown in Fig. 3, where it is held in a horizontal position on top of the segment 13. The knuckle is now open and ready for the next operation.

It will be seen that the teeth 15 of the segments are merely the operating teeth, and need not therefore be of heavy construction, since the strain will be thrown entirely on the locking teeth which are in engagement when the knuckle is locked. For this purpose, the locking teeth 38 and 39 are enlarged as shown in Fig. 6, so as to be of ample size to take the heavy strains thrown upon them. The material is therefore placed where it will be most efficient to perform its useful functions. It often happens that the knuckle pin 12 will be sheared off or thrown out, thus causing the cars to become uncoupled. In order to provide against this, the supplemental locking means are provided. It will be noted that the lugs 40 and the recesses 41 coöperate together to form a pivotal joint. If now the pin 12 should become broken or displaced,

the surfaces or shoulders *c* will be of sufficient strength to maintain the knuckle in locked position. In order that the knuckle may be readily replaced, the shoulders are 5 bent away as at 42, so as to permit the knuckle to be slipped off of the lugs 40. The shoulders or stops 43 and 44 in connection with the coöperating lugs and recesses 40 and 41 form a very rigid structure to securely maintain the coupling in closed position.

The method of operation of the air and steam connection between two cars will be obvious. It will be noted that the nipples 47 are of soft rubber and are normally 15 pressed outwardly by the springs. As the knuckles close, the nipples will engage causing them to be firmly pressed together, the soft rubber faces making a tight joint, since these faces are firmly pressed in engagement 20 by the springs 50. Due to the interconnection between the knuckle and the valve, the air and steam will be automatically turned on and off as the cars are coupled and uncoupled. The construction of the shaft for the 25 valve stem and the segment 13 permits of easy removal of the same for inspection or repairs.

It is obvious that various changes may be made in the details of construction without departing from this invention, and it is, therefore, to be understood that this invention is not limited to the specific construction shown and described.

Having thus described the invention, what 35 is claimed is:

1. The combination with a car coupling, and a fluid conduit of the character described, of a valve in said conduit having

its stem extending directly into the coupling casing and therein connected with the movable jaw by which the valve is positively moved to both open and close the conduit.

2. The combination with a car coupling, having a swinging jaw, and a fluid conduit of the character described, of a rotatable 45 valve in said conduit adapted to turn about an axis extending in the same direction as the axis of and connected with the movable jaw of the coupling.

3. The combination with a car coupling 50 having a swinging jaw, of a casing supported by the coupling head, fluid pressure pipes communicating with said casing, and a valve within the casing adapted to control the passage through the casing of fluid from 55 said pipes, the stem of said valve extending through the head of the coupling and connected therein with the swinging jaw.

4. The combination with a car coupling having a swinging jaw, of a casing supported by and depending from the coupling head, a fluid pressure pipe communicating with said casing, a rotatable valve within 60 said casing having its stem extending therethrough and into the coupling head, means 65 within the coupling head connecting the valve stem with the swinging jaw, and a handle connected with said valve by which it may be manually rotated.

In testimony whereof I affix my signature 70 in presence of two witnesses.

LOUIS N. SINGIN.
